WELL PIPE SUPPORT

Chester A. Lundeen, Los Angeles, Calif., assignor
to Byron Jackson Co., Huntington Park, Calif.,
a corporation of Delaware

Application October 3, 1939, Serial No. 297,704

11 Claims. (Cl. 24—263)

This invention relates to pipe supports for supporting and handling pipe in wells, and is directed particularly to an improved latch mechanism for such devices.

Well pipe supports, and particularly elevators adapted for use in handling drill pipe, usually comprise two segmental sections pivotally interconnected at one side and provided with latch means for releasably clamping the segments about the pipe beneath a collar or upset at the upper end thereof. In order to preclude the possibility of inadvertent release of the latch means under load, it is sometimes desirable to provide auxiliary locking means for the latch. Both the main latch and the latch lock are preferably spring-pressed towards closed position in order to be self-closing when the elevator sections are closed about the pipe.

A principal object of this invention is to provide a pipe support having a novel and improved latch mechanism of the type having auxiliary locking means.

A further object is to provide a simplified latch mechanism of the type embodying a main latch and an auxiliary latch lock, in which both the latch and the latch lock are biased toward their latching positions by a common spring means.

A still further object of the invention is to provide an improved pivotal connection between the body and latch of a well pipe elevator.

Other objects and advantages of the invention will be apparent from the following description of one embodiment and a modification thereof, taken in conjunction with the accompanying drawing wherein:

Fig. 1 is a plan view of an elevator embodying the invention, with parts broken away substantially along the section line 1—1 of Fig. 2 to disclose details of the latch mechanism in closed and locked position;

Fig. 2 is a view in front elevation of the elevator shown in Fig. 1;

Fig. 3 is a horizontal sectional view taken in the plane of section line 1—1 of Fig. 2, but showing the latch mechanism with the latch lock in released position and the latch partially open;

Fig. 4 is a view similar to Fig. 3 but showing the latch in fully released position;

Fig. 5 is a fragmentary view in front elevation of a modified construction embodying the invention; and

Fig. 6 is a sectional view taken on line 6—6 of Fig. 2.

In the embodiment of the invention illustrated in Figs. 1 to 4 of the accompanying drawing, the

novel latch mechanism has been shown as applied to an elevator of the so-called "center-latch" type comprising a pair of symmetrical sections 1 and 2 pivotally connected at one side by a hinge pin 3 and having complementary semi-circular recesses 4 and 5 on their inner faces defining a pipe bore when the segments are swung into closed position. Each section is provided with a pair of upper and lower lugs or ears 6 and 7 defining elevator link receiving recesses 8 therebetween.

A pair of horn handles 9 and 10 are provided, one projecting forwardly from the upper portion of each elevator section, to enable the operator to manipulate the sections into open or closed position. A rear handle 11 may also be provided if desired, to enable a second operator to move the elevator bodily toward or away from the pipe.

As is customary in elevators of this type, the two pivoted sections 1 and 2 are releasably latched about the pipe by cooperating latch elements on the respective sections on the side of the pipe opening opposite the hinge pin 3. A latch lug 15 is formed integral with the section 2, and is adapted to be engaged by a latch member, generally designated 16, pivotally mounted on the section 1 as by a pivot pin 17. The latch member in this form of the invention is of the U-shaped or "stirrup" type adapted to fully embrace the latch lug 15, and comprises a vertically extending leg portion 18 and a pair of upper and lower horizontally extending arms 19 and 20 having hinge lugs 21 and 22 formed on their free ends.

The elevator shown in Figs. 1 and 2 is of the type generally known as "external upset," having a downwardly tapered seat 25 in the upper portion of the pipe bore, for engagement with an external upset on the pipe. Because of the tapered seat, a considerable proportion of the weight of the pipe is converted into a radial spreading force tending to open the elevator. This force is sustained by the latch, and necessarily subjects the latch pivot pin to shearing stresses of great magnitude. In order to most effectively distribute this shearing stress and thereby reduce the stress on any given section of the pin, I have provided an upper pair of hinge lugs 26 and 27 and a lower pair 28 and 29 on the body section 1, the lugs of each pair being spaced apart only sufficiently to accommodate the hinge lugs 21 and 22 on the latch. Four shear points are thus provided, and the pivot pin is adequately supported by the hinge lugs on opposite

sides of each shear point so that no bending moments are set up.

The latch lug 15 and the latch 16 are provided with cooperating arcuate latching faces 31 and 32 respectively (Fig. 4), struck on a radius from the pivotal axis of the pivot pin 17 as a center. Inasmuch as these faces extend substantially radially toward the hinge pin 3, and hence substantially at right angles to the direction of initial separating movement of the sections 1 and 2, the spreading force exerted on the tapered seat 25 by the weight of the pipe has no tendency to release the latch 16 from the latch lug 15. In order to safeguard against accidental opening of the latch as the result of a sudden jar or blow applied to the elevator, a latch lock is provided. As most clearly shown in Figs. 1, 3 and 4, the latch lock comprises a locking finger 33 pivotally mounted on the latch 16 and engaging an abutment 34 formed on the latch lug 15. The finger 33 and abutment 34 have cooperating arcuate faces 35 and 36 respectively (Fig. 4), which are preferably struck from a center located slightly to the right of the locking finger pivot, as viewed in Fig. 1, so as to require a slight pivotal movement of the latch in the closing direction in order to release the locking finger.

It will be observed from Fig. 2 that the locking finger 33 is formed integral with an elongated hub portion 40, extending vertically between the arms 19 and 20 of the latch 16 and pivotally mounted thereon on a pivot pin 41. An operating lever or handle 42 is also formed integral with the hub 40 and the locking finger 33 and, in a manner which will be fully described hereinafter, may be manipulated to first release the locking finger from the abutment 34 and thereafter swing the latch 16 clear of the latch lug 15.

It is highly desirable that both the latch and the auxiliary lock be self-closing, and that they be yieldably maintained in closed positions, as by spring means. A salient feature of this invention is the novel arrangement whereby a single spring acts on both the latch and the latch lock to cause them both to automatically close when the elevator sections are closed about a pipe, and to exert force against both of these members to yieldably maintain them in closed position.

It will be observed most clearly from Fig. 2 that the hub 40 of the latch lock is freely journaled on its pivot pin 41, and that the latch 16 is freely journaled on its pivot pin 17. A torsion spring 45 is mounted on the pin 17 with its upper end engaging a slot in the pin and its lower end engaging the wall of the body section 1, thus tending to rotate the pin in a counterclockwise direction as viewed in Figs. 1, 3 and 4. A cam member 46 is non-rotatably secured to the pin 17, as by a transverse pin 47, and has formed thereon a cam finger engaging an arcuate cam surface 48 on the operating lever 42. The cam finger engages the cam surface at a point located outwardly of the pivot pin 41 so that the spring 45, acting through the cam 46, urges the locking finger in a counterclockwise direction into closed position. Furthermore, by reason of the fact that the locking finger is mounted on the latch 16, the spring also urges the latch in a counterclockwise direction into closed position.

A stop 51 is formed on the locking member

and is adapted to engage the cam 46 to limit the pivotal movement of the locking member in closing direction. Clockwise pivotal movement of the locking finger about its pivot pin 41 is limited by engagement of the back of the locking finger with the wall 52 of the recess in the latch portion 18, as is most clearly shown in Fig. 3. A stop 53 is formed on the cam member 46 and is adapted to engage the body section 1 to limit clockwise pivotal movement of the cam and thus limit the opening movement of the latch 16. A shoulder 54 formed on the latch 16 engages the wall of the body section 1 to limit the pivotal movement of the latch in closing direction.

Referring to Fig. 2, it will be observed that the latch pivot pin 17 is composed of two separate sections abutting each other just below the hinge lug 27. The reasons for the provision of two pins instead of a single pin are two-fold: first, if a single pin were employed the entire upper portion thereof, including the portion extending through the upper hinge lugs 26, 21 and 27, would have to be slotted in order to assemble the pin and spring with the end of the spring extending through a slot in the pin. This would materially weaken the pin and would require the use of a larger pin to provide adequate strength. Secondly, the provision of two separate pins relieves each pin of bending stresses which would be set up in a single pin as the result of slight misalignment of the upper and lower sets of hinge lugs. Even though these lugs were initially perfectly aligned, any slight inequality in wear as between the two sets of lugs would impose bending strains on a single pin extending through all six lugs. The separate pins, however, may adjust themselves independently of each other to compensate for wear.

The operation of the latch mechanism will be understood from the foregoing description. While the body sections 1 and 2 are spread apart to admit a pipe into the bore 4, 5, the latch will obviously occupy the same position, relative to the body section 1 on which it is pivotally mounted, as when the elevator is closed about a pipe and the latch is in engagement with the lug 15. As the sections are closed about the pipe, the curved nose portion of the latch engages the outwardly curved face of the lug 15 and is cammed outwardly against the action of the torsion spring, the latch and latch lock assuming the positions shown in Fig. 4. As the latch portion 18 passes over the latch lug and is pivoted inwardly by the spring, the locking finger 33 engages the outer face of the abutment 34 and is cammed to the right, into the position shown in Fig. 3. Upon further inward movement of the latch, the locking finger clears the abutment 34 and is swung in a counterclockwise direction about its pivot pin 41 by the pressure of the cam 46 on the cam surface 48. The parts thus assume the fully latched and locked position shown in Fig. 1.

When it is desired to open the elevator to release it from the pipe, the operator grasps the handle 42 and swings it to the left, against the action of the spring, to move the locking finger 33 out from behind the abutment 34. Upon engagement of the rear wall of the locking finger with the wall 52 on the latch, further pivotal movement of the locking finger about its pivot 41 is arrested, and continued swinging of the handle 42 to the left causes the locking finger and the latch to swing as a unit about the latch pivot pin 17. When the leg portion 18 of the

latch has cleared the lug 15, the stop 53 on the cam 46 engages the body section 1, thus arresting the pivotal movement of the latch about the pivot pin 17. Thereafter continued swinging of the handle 42 to the left causes the body section 1 to swing outwardly about the hinge pin 3 and away from the pipe.

In Fig. 5 I have shown the novel latch mechanism as applied to a T-head latch. Except for the specific shape of the main latch member and certain other minor structural differences, the two forms are substantially identical, and hence primed reference numerals will be used to designate parts corresponding to the parts of the first-described form designated by similar unprimed reference numerals. The latch 16' is of slightly modified T-head construction, comprising a T-head 18' adapted to engage a pair of vertically spaced latch lugs 15' and 15'' formed integral with the body section 2'. The latch is pivotally mounted on the body section 1' on a latch pivot pin 17', which is journaled in hinge lugs 27', 28', 29'. Whereas the usual T-head latch is formed with a single centrally disposed hinge lug, in the instant case the lug is bifurcated to provide space for mounting the cam member 46' on the pivot pin 17'. There is thus formed on the latch a pair of upper and lower hinge lugs 21' and 22' which are connected to the T-head by spaced arms 19' and 20'. A locking member 33', which is identical in all essential respects with the locking finger 33 of Figs. 1 to 4, is pivotally mounted on a pin 41' extending between the arms 19' and 20'.

As in the previously described embodiment, the cam 46' is non-rotatably secured to the latch pivot pin 17' by a transverse pin 47', and the pivot pin is urged in a counterclockwise direction, as viewed from above, by a torsion spring 45'. The cam 46' has a cam finger engaging a cam surface on the operating lever 42' formed integral with the locking member 33', whereby the locking member and the latch 16' are urged toward closed position.

The operative relationship of the parts and the mode of operation of the embodiment shown in Fig. 5 are identical with that shown in Figs. 1 to 4, and hence further description thereof is deemed unnecessary.

Referring once more to Figs. 1, 2 and 6, I have provided a novel and simple but effective detachable connection between the elevator ears 6 and the elevator link retaining blocks 61. As shown in Fig. 2, the blocks 61 are permanently pivotally attached to the lower ears 7, as by rivets, and are detachably secured to the upper ears to permit them to be swung outwardly to enable the elevator links to be inserted in or removed from the recesses 8. As shown most clearly in Fig. 6, the detachable connection is formed by the provision of a pair of spaced lugs 62, 63 on each ear 6, between which is disposed a lug 64 on the upper end of the retainer block 61. The lugs are provided with aligned bores into which is inserted a plain cylindrical pin 65. The pin bore does not extend entirely through the lug 63, but is reduced at its outer end at 66 to provide a shoulder 67 against which the adjacent end of the pin abuts. The reduced bore 66 permits escape of any foreign matter which may have become lodged in the lugs, and provides access of a drift pin for driving out the pin 65. It is obvious that the pin 65 must be inserted through the lug 62, and is retained within the aligned bores by a removable closure such as a pipe plug 68 threaded into a boss formed

on the lug 62. Both the pin 65 and its retaining means are thus wholly enclosed within the ear 6, with no protruding parts subject to being broken off or accidentally loosened.

5 It will be observed from Fig. 1 that the operating handle 42 is disposed directly beneath the handle 10 and is thus protected against being accidentally struck from above. It will be understood that, if preferred, a pair of loop handles 10 as in Fig. 5 may be used in lieu of the horn handles shown in Figs. 1 and 2, thus protecting the operating handle from the front and below as well as from above.

15 While I have shown the novel latch mechanism as applied to a "center latch" type of elevator, it will be understood that it is equally applicable to other types of elevators, such, for instance, as a "side door" elevator. Also, as illustrated in Fig. 5, it is not limited in its application to elevators for handling external upset pipe, but is 20 equally applicable to collar-type elevators as well as to slip elevators and other sectional supporting devices adapted to be latched about drill pipe, well casing, or tubing.

25 I claim:

1. In an elevator comprising a pair of pipe-engaging body members pivotally connected at one end and adapted to be releasably latched together at their free ends: latch mechanism therefor comprising a pair of angularly related shoulders on one of said members; a latch member pivotally mounted on the other of said members and adapted to engage one of said shoulders; a locking member pivotally mounted on said latch member and adapted to engage the other of said shoulders; and spring means acting between said other body member and said locking member and yieldingly urging the latter into engagement with the second-mentioned shoulder, said spring means also urging said latch member into engagement with said first-mentioned shoulder through the pivotal mounting of the locking member on the latch member.

2. In a well pipe supporting device comprising 45 a pair of pipe-engaging body members pivotally interconnected at one end and adapted to be releasably latched together at their free ends, latch means comprising: a shoulder formed on one member; a latch member pivotally mounted 50 on the other body member and adapted to engage said shoulder; a second shoulder formed on said one member; a locking member pivotally mounted on said latch member and adapted to engage said second shoulder; and common spring-pressed means pivotally mounted on said other member 55 on the pivotal axis of said latch member and operatively associated with said latch member and said locking member for yieldingly urging both said latch member and said locking member 60 into engagement with their respective shoulders when said body members are closed about a pipe.

3. In a well pipe support comprising a pair of pipe-engaging body members pivotally interconnected at one end and adapted to be releasably latched together at their free ends, latch means 65 for releasably latching said free ends together comprising: a shoulder formed on one member; a latch member pivotally mounted on the other member and adapted to engage said shoulder; locking means for releasably locking said latch member to said shoulder and comprising a second shoulder on said one member and a locking member supported by said other member and adapted to engage said second shoulder; and common spring means for yieldingly urging both said

latch member and said locking member into engagement with their respective shoulders comprising a spring-pressed member pivotally mounted on said other body member.

4. In a well pipe support comprising a pair of pipe-engaging body members pivotally interconnected at one end and adapted to be releasably latched together at their free ends, latch means for releasably latching said free ends together and comprising: a shoulder on one member and a latch pivotally mounted on the other member and adapted to engage said shoulder; lock means for releasably locking said latch to said shoulder and comprising a second shoulder on said one member and a locking member pivotally mounted on said latch and adapted to engage said second shoulder, and common spring means interposed between said other body member and both said latch and said locking member for yieldingly urging both said latch and said locking member into engagement with their respective shoulders.

5. In a well pipe supporting device of the type comprising a pair of body members adapted to encircle a pipe and hinged together at one end for relative swinging movement into closed and open positions in combination with means for releasably latching said members in closed position, the latching means which comprises: a main latch pivotally mounted on the free end of one of said members for horizontal swinging movement toward and away from the free end of the other member, a shoulder on said other member adapted to be engaged by said latch when the latter is closed, an auxiliary latch supported by said first-mentioned member, a second shoulder on said other member angularly disposed with respect to said first-mentioned shoulder and adapted to be engaged by said auxiliary latch to maintain said main latch in closed position, and common spring means interposed between said other body member and both said latch and said locking member for yieldingly urging both said main latch and said auxiliary latch toward their closed positions.

6. A well pipe support comprising: a first body member adapted to in part encircle a pipe, a latch member, and means for pivotally attaching it to said first body member, said means including upper and lower vertically aligned pairs of pivot ears formed on one of said members, and upper and lower pivot ears on the other of said members, each of the latter ears being disposed between a pair of ears on the one member, a pair of pivot pins each interconnecting one of said pair of ears to the ear disposed therebetween, a torsion spring mounted one of said pins and operatively connected thereto, a cam member non-rotatably mounted on said one pin, a second body member hinged to said first body member and cooperating therewith to encircle a pipe, a latch shoulder on said second body member, and an operative connection between said cam member and said latch member whereby said latch member is yieldingly urged by said spring into latching relation with said latch shoulder.

7. A well pipe support comprising: a first body member adapted to in part encircle a pipe, a latch member pivotally mounted on said body member, one of said members having aligned pivot ears, and the other having pairs of aligned pivot ears between which said aligned pivot ears of the one member are disposed, separate pivot

5 pins individual to each of said pairs of pivot ears and interconnecting them with the associated pivot ear on the one member, one of said pivot pins being freely rotatable relative to its associated pivot ears, a second body member hinged to said first body member and having a latch shoulder thereon adapted to be engaged by a latch surface on said latching member, another of said pivot pins being operatively connected with said latch member and being spring-pressed in a direction to yieldingly urge said latch member into engagement with said latch shoulder.

10 8. An elevator comprising: a first body member adapted to in part encircle a pipe, a latch member, one of said members having upper and lower vertically aligned pairs of hinge lugs and the other member having an upper hinge lug disposed between the upper pair of hinge lugs on the one member, and having a lower hinge lug disposed between the lower pair of hinge lugs on said one member, hinge pin means interconnecting the hinge lugs on one member with those on the other member, a second body member hinged to said first body member and cooperating therewith to encircle a pipe, said second body member having a latch shoulder thereon, and said latch member having a latching surface adapted to engage said shoulder.

15 9. An elevator as set forth in claim 8, in which said hinge pin means comprises an upper hinge pin interconnecting said upper hinge lugs and a separate lower hinge pin interconnecting said lower hinge lugs.

20 10. In an elevator comprising a pair of pipe-engaging body members pivotally connected at one end and adapted to be releasably latched together at their free ends; latch mechanism therefor comprising: a pair of angularly disposed shoulders on one of said members; a latch member pivotally mounted on the other of said members and adapted to engage one of said shoulders; a locking member pivotally mounted on said latch member and adapted to engage the other of said shoulders, said locking member having a cam surface thereon; a cam member pivotally mounted on said other body member and having a cam surface engageable with said first-mentioned cam surface, and spring means yieldably urging said cam member about its pivotal axis in a direction to exert pressure on said locking member urging it into engagement with the other said shoulder.

25 11. In an elevator comprising a pair of pipe-engaging body members pivotally connected at one end and adapted to be releasably latched together at their free ends, latch mechanism therefor comprising: a pair of angularly disposed shoulders on one of said members; a latch member; means including a pivot pin journaled in said other body member and in said latch member for pivotally supporting said latch member for rocking movement into and out of engagement with one of said shoulders; a locking member pivotally mounted on said latch member for rocking movement into and out of engagement with the other of said shoulders; a cam member fixed to said pivot pin and engaging said locking member, and a torsion spring mounted on said pivot pin and operatively connected thereto to urge said cam member about its pivot into engagement with said locking member.
